GARMENT HANGER

Edward Okun, New York, N. Y.

Application April 16, 1936, Serial No. 74,612

3 Claims. (Cl. 223—94)

This invention relates to improvements in garment hangers and more particularly to improvements in collapsible garment hangers.

A particular object of this invention is the provision of an improved collapsible garment hanger preferably made of metal which is foldable into a small compass when collapsed and which will be of superior efficiency for holding garments when in the operative position.

10 Further objects of the invention will be apparent from the specification and drawing in which:—

Fig. 1 is a perspective view of my improved hanger in partly extended position.

15 Fig. 2 is a perspective view of my improved hanger in fully extended and operative position.

Fig. 3 is a top plan view of my hanger in folded or collapsed position.

20 Fig. 4 is an enlarged detail sectional view along the line 4—4 of Fig. 2.

Fig. 5 is an enlarged detail sectional view along the line 5—5 of Fig. 1.

25 10 and 11 denote the central links of a folding or lazy-tongs construction which comprises the body of the hanger. 12, 13, 14 and 15 denote links of said construction which are pivoted to each other and to the members 10 and 11 at 16, 16', 17 and 17', 18 and 18'. 19 indicates the central pivot member of the members 10 and 11. 20 designates a rigid extension of the link 13; 21 a similar extension of the link 15. The extensions 20 and 21 each end in a dish-like element 22 of substantially oval contour, 22' representing the base of said dish-like element which has superimposed thereon a soft textile material 23 which is enclosed by the rim or flange 24.

30 I have illustrated in this embodiment a particular shape of extension 20 or 21, but I may vary the shape of this arm and dish-like element 22 without departing from the spirit of my invention.

The purpose of the layer 23 of textile material made of velvet, plush or the like, or other material provided with a nap, is to serve as a frictional device to impede the falling-off of garments which are suspended upon the hanger. Fig. 5 shows the construction of each of the pivot members.

25 25 indicates the head of the pivot member. 26 50 is the base of the pivot member, which is enlarged in order to turnably connect the adjacent parts, sufficient play being allowed so that said parts can turn freely.

The shanks of pivot members 16 and 16' pass 55 through lugs 27 which hold the end-links 28 of

a chain 29 which can be used for hanging ties, belts, scarfs and the like. The pivot member 19 is provided with an upper extension 30 having a pivot pin 32 to receive the hook 31 by which the hanger may be suspended. The hook 31 is mounted so that it is movable in any desired direction since the extensions 30 can be moved around a vertical axis, and the hook 31 can be turned around a horizontal axis.

It should be noted that in operative position 10 the shank 35 of the hook 31 is at right angles to the plane of the links 10, 11, 12, 13, 14, and 15, so that the pressure of the garment suspended from the hanger is directed parallel to the shank 35 and does not tend to collapse the lazy-tongs 15 construction, so that the links of said construction will remain in any desired position.

I am aware of the fact that garment hangers have previously been constructed on a series of levers and links designated as lazy-tongs, but in such construction the weight of the garment has tended in all cases to force the lazy-tongs into the maximum extended position, whereas, by the arrangement herein indicated, the lazy-tongs may be kept at any position desired according to the 20 size of the garment suspended on the hanger.

I preferably employ a gauge of metal for the manufacture of the links so that the hanger will be sufficiently springy to conform to the shape of the garment, and my improved hanger in its 25 operative position will conform to the contour of the ordinary garment hanger.

As shown in Fig. 3, the links 10 and 11 are of equal length, and said length is equal to the length of link 15 and its extension 21, including 30 the dished member thereof, and is equal to the length of link 13 including the extension 20 and the dished member thereof. The ends of the parts of the collapsed device are closely adjacent each other and the hook lies flat against the collapsed body of the device. The length of the hook 35 is substantially equal to one-half the length of member 10 or member 11.

Having fully described my invention, what I 40 claim is:—

1. A lazy-tongs hanger comprising a pair of arms of equal length, a pivot member turnably connecting said arms to each other at their central points so that the outer ends of said arms are arranged in pairs, the outer ends of each pair 50 being movable relative to each other, the outer ends of each pair having a pair of links pivotally connected thereto, each pair of links comprising a short link and a long link, the length of the long link being substantially equal to the length 55

of an arm, the short link being pivotally connected to the long link at the central point of the long link, the extensions of the long links beyond the short links constituting the end-portions of the hanger and a hook turnably connected to said pivot member and turnable in a direction perpendicular to the direction of turning movement of said arms.

2. A lazy-tongs hanger comprising a pair of arms of equal length, a pivot member turnably connecting said arms to each other at their central points so that the outer ends of said arms are arranged in pairs, the outer ends of each pair being movable relative to each other, the outer 15 ends of each pair having a pair of links pivotally connected thereto, each pair of links comprising a short link and a long link, the length of the long link being substantially equal to the length of an arm, the short link being pivotally connected to the long link at the central point of the long link, and a hook turnably connected to said

pivot member and turnable in a direction perpendicular to the direction of turning movement of said arms, the ends of said long links which project beyond the short links constituting the end-portions of the hanger and having cup-shaped depressions having fabric members held therein. 5

3. A lazy-tongs hanger comprising a pair of arms of equal length, a pivot member connecting said arms to each other, the outer ends of said arms being arranged in pairs, the outer ends of each pair being movable relative to each other, the outer ends of each pair having a pair of links pivotally connected thereto, each pair of links comprising a short link and a long link, the short 15 link being pivotally connected to the long link intermediate the ends of the long link, the extensions of the long links beyond the short links constituting the end-portions of the hanger, said arms having supporting means connected thereto. 20

EDWARD OKUN.
